US0D1006484S

(12) United States Design Patent (10) Patent No.: US D1,006,484 S
(45) Date of Patent:  Dec. 5, 2023

(54) HOLDER FOR SANITARY FLUID DISPENSER

(71) Applicant: ADA Cosmetics International GmbH, Kehl/Baden (DE)

(72) Inventors: Johannes Schmidt, Kehl/Baden (DE); Mitja Cepin, Šencur (SI)

(73) Assignee: ADA Cosmetics International GmbH, Kehl/Baden (DE)

() Term: 15 Years

(21) Appl. No.: 35/515,013

(22) Filed: Apr. 11, 2022

(80) Hague Agreement Data

Int. Filing Date: Apr. 11, 2022

Int. Reg. No.: DM/222860

Int. Reg. Date: Apr. 11, 2022

Int. Reg. Pub. Date: Aug. 26, 2022

(51) LOC (14) Cl. 23-08

(52) U.S. Cl.

USPC D6/545

(58) Field of Classification Search

USPC D6/512, 515, 518, 522-525, 536, 540, D6/542, 545, 567, 571, 572

CPC A47K 5/12; A47K 5/1202; A47K 5/1211; A47K 5/1214
